UNITED STATES PATENT OFFICE.

FREDERICK E. ALDERDICE, OF NEW YORK, N. Y.

RACING GAME.

Application filed January 11, 1928. Serial No. 245,893.

This invention relates to a novel toy and more particularly to a toy including several movable figures which may be operated in the same direction to simulate a race between real objects of which they are shaped to simulate.

The obvious purposes is to provide a game of this character which will be highly amusing for children and adults, and induces interest in games of contest.

The paramount object of this device resides in providing a pair of movable figures, which when they have reached the end of the course provided for their travel, they may be reversed for travel in the opposite direction, with but a minimum of interval.

Another object is appreciated by the fact that the device is of very simple construction, which will obviously render the same reasonable to manufacture, and of low cost to retail.

After reading the following specification and claims, other very novel objects and advantages will readily become apparent.

25 In the drawings:—

Figure 1 represents a top plan view of the toy race horse with the figures mounted for movement thereon.

Fig. 2 represents a longitudinal sectional view through the device, disclosing the manner of operation, while

Fig. 3 is a fragmentary view in perspective of a detail.

Now for a more detail description of the invention, reference is made to the drawing in which like numerals designates like parts of the invention. The numeral 1 designates a substantially rectangularly shaped plate 1 having suitable indicia thereon simulating 35 preferably separate territories, such as for instance the Eastern and Western hemispheres separated by the Atlantic Ocean.

In the particular disclosure of this invention, a pair of aeroplanes 2—2 are mounted 45 for movement on parallel courses. This plate 1 is formed with a pair of longitudinally extending slots 3—3, which slots terminate inwardly from the respective ends of the plate. The periphery of the plate is provided with a depending supporting flange 4, whereby the plates may be supported in spaced relation from a supporting surface, so as to accommodate the operating mechanism of the device.

A threaded rod 5 is journaled at its opposite ends through bushings 6 secured within the depending flange 4, at the opposite ends of the plate. This threaded rod is adapted to be supported in direct underlying position with one of the slots 3, in the plate, while one end portion of the rod projects a substantial distance beyond the depending flange, so that the same may be shaped to provide a crank 7 having a suitable handle 8.

The opposite end of the threaded rod has a nut 9 threaded thereon, exteriorly of the flange, so as to prevent the inward movement of the rod.

As is shown in Fig. 2, each end of the threaded rod may be formed with a crank if so desired, whereby a person may occupy a place at respective ends of each course, so that upon the completion in travel of the plane in line direction, the person at the opposite end of the course, may nose the plane in the reverse direction, and move the plane by a reverse rotation of the rod 5.

An internally threaded block 10 is provided with an upstanding tubular post 11 adapted for projection through the slot 3 of the plate. This post is formed with notches 12 at diametrically opposite portions at the upper end thereof, to receive the laterally projecting pins 13 of an elongated stem 14. One of the aeroplanes 2 is adapted to be mounted upon the upper end of this stem, while the lower portion of the stem is to depend within the tubular post 11, so that the ends 13 may seat in the notches 12 for maintaining the aeroplane pointed in a given direction.

Obviously, when the block 10 is in relation with the threaded rod as clearly shown in Fig. 2, and the aeroplane is supported in the manner before stated, the rotation in clockwise direction will cause the plane to move toward the left. When the plane has reached the end of the slot 3, the plane and stem 14 may be lifted, so as to disengage the ends 13 from the notches 12, whereby the stem may be given a semi-circular movement so as to reverse the position of the plane.

Having thus described my invention, what I claim as new is:

In a toy of the character described, an elongated plate, said plate being formed with a longitudinally extending slot, a support

at each end of the plate, a threaded rod journaled at each end through the respective supports, a block having a threaded bore adapted to receive the threaded rod, a tubular post on the block, a stem extending longitudinally within the post and adapted to project above the same, a figure mounted

upon the projecting end of the stem, and means between the stem and the post whereby the figure may be moved to face in a reversed direction. 10

In testimony whereof I affix my signature.

FREDERICK E. ALDERDICE.
